DRILL STEEL CENTRALIZER

Filed July 27, 1926

INVENTOR
Charles C. Hansen
BY Webster & Odur
HIS ATTORNEY.

UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

DRILL-STEEL CENTRALIZER.

Application filed July 27, 1926. Serial No. 125,239.

This invention relates to rock drills of the hammer type and especially to a device for the purpose of centralizing the drill steel. The invention provides features of 5 novelty when applied to guiding and centralizing the drill steels of channeling drills.

An object of this invention is to cause the drill steel to strike repeated blows on the same spot during the process of broaching or of starting the hole to be drilled, especially when the rock surface is inclined 10 to the axis of the drill steel.

Further objects of this invention will hereinafter appear and can be more clearly 15 explained by reference to the accompanying drawings in which—

Figure 1 is a side view of the end of a drill shell with the centralizer mounted thereon and the drill steel in its proper position with respect to the drill shell and the 20 drill centralizer,

Figure 2 is an enlarged cross sectional view of the centralizer,

Figure 3 is a longitudinal sectional view 25 of the centralizer showing the wearing blocks in position and showing the method of attaching the centralizer to the drill shell,

Figure 4 is a longitudinal sectional view 30 of the centralizer showing a pair of wearing blocks removed to receive a drill steel of rectangular cross section, as for instance a channeling bar, and

Figure 5 is a perspective view of one of the removable wearing blocks.

Referring to the drawings a rock drill 35 front head A is part of a suitable rock drill mounted on the shell B. A drill steel C extends in the well-known manner into the front head A to receive blows of impact 40 delivered by the hammer piston or anvil block, (not shown) depending on the type of rock drill employed. The rock drill is slidably mounted upon the shell B and may be moved forward or backward in order 45 to keep the cutting end of the drill steel C in contact with the rock or to remove the tool from the hole. This longitudinal movement may be accomplished by means of a feed screw (not shown). The function 50 of the centralizer is to keep the bit E of the drill steel C on the desired point on the rock while permitting longitudinal motion of the drill steel C. Motion in any other direction is prevented.

Centralizers are especially adapted to be

used in certain quarrying methods which require that a row of holes F (Fig. 1) be drilled to a certain depth and that the partitions or walls between these holes be broken out by means of a specially shaped co 5 drill steel, known as a channeling or broaching bit.

In accordance with the above mentioned requirements the centralizer includes a frame H rigidly secured to the drill shell 65 B (Fig. 1) by bolts J extending longitudinally of the shell. The frame H is spaced from the end of the shell B by suitable spacers or washers J' about the bolts J. Preferably the frame H is U shaped having 70 outwardly extending arms H' on either side of the drill steel C. Each arm H is formed of two projections between which a bolt K is pivotally mounted, the threaded end of the bolt K being adapted to extend 75 beyond the ends of the arm H'.

In order to secure wearing blocks N firmly in place, a wearing block O is provided closely fitting within the parallel arms of the primary yoke M and secured thereto 80 by means of bolts P. In addition to securing wearing blocks N firmly in place, the wearing block or secondary yoke O provides a suitably shaped recess for a drill steel of different cross sectional shape if the 85 wearing blocks N are removed.

Between the arms H' the U shaped yoke M is adapted to be removably secured by the bolts K.

The drill steel C is adapted to be held 90 slidably in place by means of the wearing blocks O, N and Q. These blocks placed in the positions described form a cylindrical opening R to accommodate the round drill steel C.

Figure 5 shows the shape of each of the wearing blocks N. This block has two parallel faces W, a concave face S to bear against the steel C, an opposed plane face T and a head or flange to assist in holding 100 the blocks N in position between the blocks O and Q.

In Figure 3 the wearing blocks N are shown in place. This assembly shows in dash-dot lines a round drill steel C occupying 105 the cylindrical recess formed by the wearing blocks N, the secondary yoke or wearing block O, and the wearing block Q.

In Fig. 4 the wearing blocks N and the round drill steel C are removed and a rec- 110

tangular drill steel C' placed in the rectangular recess so formed.

The flanges V (Figs. 4 and 5) are for convenience in assembling and to insure accurate placing of the blocks N and Q and the secondary yoke O.

Special advantages of this invention are the convenience of assembly and the rapidity with which the round drill steel may be replaced by one of rectangular cross section. To accomplish this change the drill steel is first withdrawn from the hole F in the rock by means of the longitudinal feed screw, the bolts K are loosened and swung sideways to permit removal of yoke M and the blocks N; and the rectangular broaching steel C' is placed in the centralizer leaving out the

blocks N and refastening the yoke M in place by means of the bolts K.

I claim:

A drill steel centralizer comprising a frame, a pair of pivotally mounted bolts, a yoke clamped rigidly to said frame by means of said bolts and having two parallel arms, and removable wearing blocks in said yoke, said yoke holding said wearing blocks firmly in place, a pair of said wearing blocks adapted to be removed to accommodate drill steels of different cross sectional shape.

In testimony whereof I have signed this specification.

CHARLES C. HANSEN.
